Application May 28, 1947, Serial No. 751,082

11 Claims. (Cl. 273—50)

1

The present invention relates generally to signal devices and more particularly to foul detecting means for games and recreational contests such as bowling, and constitutes a continuation-in-part of our Patent No 2,425,255.

The present invention is illustrated by way of example as an automatic foul detecting device for bowling alleys to operate or trigger the operation of equipment installed upon the alley, such as lights, foul signals, pin setters, score keepers, warning devices and penalizers, or the like, which are used during the play of the game.

The game of bowling is played on an alley having a runway for players and a ballway for handling a ball put into play by the players. A foul line defines or separates the two ways, and when delivering a ball across the foul line a player is not permitted to touch the foul line or the ballway with any part of his body. Furthermore, no limb or appendage of his body may overhang the foul line while it is also in contact with the runway without a foul being deemed to have been committed.

The pins to be knocked down by a ball are set in a triangular pattern near the far end of the ballway, and as a part of the alley, a pit is provided beyond the pins to catch the ball and any pins it knocks down.

There are ten frames to a game for each player, and in each frame the player is permitted to throw two balls in an endeavor to knock down all of the pins. The number of pins knocked down in each frame is added, according to certain scoring rules, to the number in the other frames to make the total score for the game, and the penalty for committing a foul is the loss in the total score of the pins knocked down by the ball which was thrown when the foul was committed and also the loss of the ball thrown.

This is significant because each frame starts with all the pins set up on the alley, and if a foul is committed on the first ball delivered in any frame, all the pins knocked down but not scored are set up again on the alley for the second ball. Consequently, the resetting of all of the pins will take place each time a foul is committed, and a foul signal is generally provided which not only instructs a pin boy to reset the pins but also informs the player that a reset is being made. Because of this resetting of all the pins on the ballway following each foul committed, players have upon occasion yielded to the temptation to commit an intentional foul if they discover in time to do so that the first ball leaves or will leave a difficult play for them on

2

their second ball. The odds on being able to knock down all the pins on one ball are much greater than the odds on being able to pick up on the second throw two widely spaced pins, referred to in bowling parlance as a "split" or "railroad."

In this connection, equipment has been employed for many years to assist in resetting the pins, namely, a foul signal and a pin rack which is loaded by a pin boy. Whenever a foul is detected and signalled, the pin boy lowers the rack to flip the pins into place on the ballway.

If the pin setting rack is operated by a prime mover to lower the pins and set them in place on the alley its action can be initiated or triggered directly with the foul signal impulse or it can be initiated in conjunction with the foul signal by an automatic foul detector or by a human foul judge himself. The end result would be the same as that which would occur with a pin boy who operates the rack by hand for the same purpose when informed of the commission of a foul by an automatic foul detector or human foul judge.

25 However, not all fouls committed when "railroads" are left are unintentional fouls, and in the present invention one of the objects is to provide an improved foul detecting device which prevents the sly intentional commission of a foul to bring about unfairly a resetting of the pins by hand or automatic racks.

A further object of the invention is to provide an improved foul detecting device which distinguishes between a delayed sly movement of a foot upon or over the foul line and a movement wherein the player cannot prevent falling over the foul line.

Another object of the invention is to determine in relationship to the play of the ball the periods of time within which infractions of the rules of play will be considered involuntary fouls on different areaways of the alley.

40 A further object of the invention is to provide a foul detecting device which removes from the conjecture of observers the character of infractions of rules of play where the question of intention is not clear, and provide continuing foul detection for those infractions where the intention of the player is clearly discernible.

45 A further object of the invention is to remove from foul detection within a predetermined period of time after the ball has been delivered the devices which detect fouls that are generally committed by the time the ball has reached the 50 pit and continue for a predetermined time there-

after the detection of fouls which are delayed and generally involve the loss of balance.

Another object of the invention is to provide a compact and simple unit of equipment which is inexpensive to manufacture and maintain and can be readily installed upon a bowling alley and serviced easily from time to time as required.

These being among the objects of the present invention other and further objects will become apparent from the drawings, the description relating thereto and the appended claims.

Referring now to the drawings:

Fig. 1 is a vertical section taken longitudinally through a bowling alley indicating the arrangement and preferred construction of the interlocked devices that detect and disclose infractions of the rules of play;

Fig. 2 is a fragmentary view taken from above the alley, of the alley shown in Fig. 1;

Fig. 3 is a diagrammatical showing of a photoelectric control system employed to detect infractions of rules of play at and beyond the foul line;

Fig. 4 is a diagrammatical showing of a modified photoelectric control system to detect infractions of rules of play at and beyond the foul line;

Fig. 5 is a preferred form of the photoelectric control system to detect infractions of rules of play at and beyond the foul line; and,

Fig. 6 is a diagrammatical detailed showing of a typical photoelectric control employed in the embodiment shown in Fig. 5.

Reference is hereby made to our Patent No. 2,425,255 of which this application is a continuation in part and to the disclosure and description therein which is hereby incorporated herein to show other embodiments of the invention and for a better understanding of the presently disclosed improvements.

Referring now to the drawings more specifically, the bowling alley indicated at 10 comprises a bed 11 divided by a foul line 12 into a runway 13 upon one side and a varnished portion or ballway 14 upon the other side over which the ball 15 travels to reach and strike the bowling pins 16 that are set up on the far end of the alley. Along both sides of the ballway, the alley 10 is bounded by gutters 17 and the gutters by rails 18, each rail separating adjacent alleys one from another where more than one alley is installed.

At the ends of the rails 18 that are adjacent the foul line 12, the rails are cut away as at 20 to receive a box 21 in which are mounted the light sources for the light beams for one alley and, shielded therefrom, the two photoelectric cells for an adjacent alley, and also preferably, the circuits which are employed to detect infractions of rules of play at the foul line.

More particularly, as shown in Fig. 1, two beams of light are arranged one above the other for each alley at the foul line 12. The top beam 23 is located where it is interrupted by a ball approaching the foul line before the lower beam 24 is interrupted, and is the last of the two beams to be reestablished as the ball rolls beyond the foul line, it being impossible thereby to interrupt the lower beam 24 with a bowling ball without interrupting the top beam 23 first. The beam can be round or of a cross-sectional size and shape corresponding to the size and shape of the aperture or target at which it is directed on the opposite side of the alley.

Furthermore, if desired, a trip beam device 25 may be employed down the alley a short way to control a normally closed switch 26 that is held

open by energization of a relay 53a to prevent registering an infraction of the rules of play as a foul unless the ball is released to pass down the alley. Interruption of the beam of the device 25 operates to close the switch 26 by means of a circuit described in further detail herein-after in connection with Fig. 3.

Furthermore, another circuit similar to that controlled by the beam 25, which will also be described later, may be controlled by a beam device 27 located just in front of the pins 16 to open a normally closed switch 28 (Fig. 3) held closed by energization of the relay 53b. This switch is permitted to open when a ball passes that point to prevent a player from committing an intentional foul when he sees that the ball has struck the pins and left them in such a way as to provide the player with a difficult second try. The photoelectric controls 25 and 27 and the operation of the switches 26 and 28 will be described further in their relation to the light beams 23 and 24, it being understood that the photoelectric controls 25 and 27 can be dispensed with in any installation if the results accomplished by them are not desired by the alley owner. Referring now to Fig. 3 a foul signal lamp 41 is connected in parallel with any other form of alarm desired that is connected to the terminals 151. The lamp 41 and terminals 151 are connected in series with the normally open switches 44 of a normally deenergized relay 45 for automatic operation. Relay 45 has a self-sustaining circuit 107 connected to one of the contacts of a switch 44 to energize the relay 45 and close the switches 44 controlled thereby until such time as a normally closed bimetal timing switch 47 breaks after being heated by a heater unit 48.

The relay 45 is powered from the current source 42, through a conductor 100, normally open switch 50, a conductor 101, normally closed switch 28, conductor 102, the coil of the relay 45, conductor 103, a normally closed switch 52, conductors 104 and 105, normally closed switch 47, and conductor 106. The relay 45, once actuated, closes the switches 44, after which the energization of the relay 45 is self-supported through conductors 100 and 107, the lower of the switches 44, conductor 103, switches 52 and 47 and conductors 105 and 106.

In addition to the energization of the relay 45 being self-supporting through conductors 103, 104 and 105, current is passed through the heater coil 48 through conductors 108 and 106. The upper of the switches 44 actuates the light and alarm through conductors 100, 107, 110, switch 26, and conductors 105 and 106 as controlled by the timer switch 47.

The normally closed relay switch 26 is held open by the coil 53a as described in connection with the trip beam 25 located where it will detect the release of the ball. The switch 26 is disposed preferably in the foul signal circuit 46 so that it does not interfere with the action of the relay 45, but rather cooperates with its action, being in series with the upper switch 44 thereof.

The relays 53a and 53b differ from relay 53 in that they act quickly but have a delayed recovery from their resting position once the resting position is attained.

For a better understanding of the general organization of the photoelectric circuits as they control the relays, it is the intention to use the beam 23 and relay 53 to lock out the system instantly whenever the ball goes through, and to return the system to operation instantly when

the ball clears the beam 23. The lower beam relay 51 is instantly responsive to slight or partial interruptance of the beam 24. Until the beam of light energizing device 27 has been interrupted the relay 45 may be closed by the interruptance of the beam 24 alone and held closed by the timer switch 47. Then when the ball 15 trips the beam 25, signifying that it has been released and put into play, the switch 26 closes and operates a signal lamp 41 to indicate that the infraction interrupting the beam 24 was a foul. On the other hand, if a foul has not been committed until after the ball interrupts the trip beam 25, closure of the switch 26 merely sets up the circuit controlled by the relay 45, and the lower beam registers a foul if committed before the ball interrupts the beam 27.

Thus when a player advances to the foul line 12 to place a ball 15 in play by delivering it down the alley in the direction of the pins 16, any infractions of the rules of play at the foul line will be detected by the beam 24 and registered by the relay 45 closing the switches 44 and sustaining the closure as timed by the duration of the closed period of the timer switch 47. Whether the ball has been released before or after the infraction, the registry will be established since, if the ball interrupts a beam 23, the relay 45 is released or locked out only to let the ball go through and, if the infraction takes place or continues to exist after the ball has been released, the moment the upper beam 23 is reestablished the relay 45 will be energized.

Energization of the relay 45, however, does not sound the signal and indicate the foul immediately unless the beam 25 is dispensed with, in which case the foul will be immediately indicated. If the beam 25 is employed in any particular installation, the recording of the foul will not be made until the beam 25 is interrupted and the switch 26 permitted to close.

The beam 25, when employed, is installed far enough down the alley that it is unlikely that a ball will be thrown over it and low enough upon the alley to catch the ball rolling past it. Although it is desirable to have the beam 25 as close to the foul line as possible to apprise a player of his foul as soon as possible for psychological reasons, the distance that beam 25 is beyond the foul line is not critical so long as a slow moving ball will interrupt it within the timing period provided by the duration of the closed position of the timer switch 47. Thus a foul is registered and then indicated if a ball has been put into play.

In order to prevent a player committing an intentional foul to better his chances on a second try or to prevent facetious fouling merely to work the apparatus after the play of the ball has been completed, it is preferred that a beam 27 be located just in front of the pins to remove the foul detector from operation when or shortly after the ball has struck the pins 16.

Referring to Fig. 1, cascade beams 111 are provided over the ballway immediately beyond the foul line 12 to cover an area of about two to four feet with the zig-zag beams sufficiently close together that persons falling over the foul line, as when they lose their balance, will interrupt at least one of the beams. These beams, by way of example, originate with a light source at 112, and are projected by lenses 113 at a slight angle to the opposite side of the alley where a mirror 114 catches the light and reflects the light back to a second mirror 115, which mirror in turn reflects the light to a third mirror 116, from which

mirror the beam is reflected again across the alley to a point 117 where it is picked up by a photoelectric cell 118 (see Figs. 3, 4 and 5). As many cascades as may be desired can be provided in the manner described and the photoelectric cells 118 can be connected in series with the grid circuit of the cascade amplifier indicated at 120 in Figs. 3, 4 and 5, a representative form of another such amplifier being shown in Fig. 6.

The amplifier circuit shown in Fig. 6 is built around the R. C. A. 117P7GT tube 121 of a heater cathode type which combines in one bulb a half wave rectifier 122 and a beam power amplifier 123. The heater 124 is designed for use directly across a 117 volt supply line which can be either A. C. or D. C. provided the rectifier side of the filament such as the binding post (7) 125 is connected to the positive side 129 of the D. C. power leads, or the ground line 119 of the A. C. circuit is connected to the amplifier side of the heater 124 as at terminal 2 indicated at 126. A smoothing choke 127 is connected to the cathode of the rectifier side and both leads thereof are provided with smoothing condensers 128 leading to the ground line 119. If D. C. current is to be used, the choke 127 can be a resistance of such value that the voltage on the B+ supply line indicated at 130 will be approximately 85 volts so that it will not overload the photoelectric tube 118.

A relay coil 131 is connected between a B+ line 130 and a plate 132 of the amplifier side 123 of the tube 121. An anode 133 of the photoelectric cell 118 is connected to the B+ line 130 while a cathode 134 thereof is connected to the ground line 119 through a high resistance 135 of approximately 5 megohms to maintain a small current flow in the photoelectric circuit. A coupling condenser 136 of approximately .01 mfd. value connects the cathode 134 of the photoelectric cell to grid 137 of the amplifier tube 123 whereby the current flow through the relay 131 is controlled by the variation of light upon the photoelectric cell 118 through bias of the grid 131. In this particular circuit the flow of relay energization current is maintained as long as there is light falling upon the photoelectric cell 118. When the beam of light directed against the photoelectric cell 118 is interrupted, the relay 131 is deenergized.

Referring to Fig. 5, the rectifier side of the tube 121, for purposes of convenience, is shown as a battery 140, while the amplifier side of the tube 121 is indicated in a simplified form as a triode 141. The photocell 36 is the one responsive to the lower beam at the foul line and the photocell 34 is the one responsive to the upper beam at the foul line, like numerals referring to like parts throughout the views. The beam device 25 is the one located upon the alley approximately twenty feet down the alley beyond the foul line, and the beam device 27 is located on the alley either in front of the plane 16 to be actuated by the ball at that point or some place in the pit.

The system shown in Fig. 5 is shown in the condition of energization prior to the time the ball 15 is put into play over the foul line by a player on the runway 13. In this condition, all photoelectric relays are energized, namely, relay 53 for the upper beam 23, relay 51 for the lower beam 24, relay 53a for the trip beam 25, which has a 10-second hold after deenergization, relay 53b for the cutout beam 27, which has a delay hold of approximately 8 seconds, and relay 142 for the cascade beams. The upper beam relay 53 has two switches thereon, a normally closed

one 143 held open when the relay 53 is energized, and a normally open one 144 held closed when the relay is energized. The lower beam relay 51 has one normally open switch 145 thereon held closed when energized. The cascade relay 142 has one normally closed switch 146 thereon held open when energized. The trip beam relay 53a has a single pole double throw switch 200 thereon whose contact 148 is open and whose contact 147 is closed when energized, and the cutout relay 53b has one normally closed switch 150 which is held open by the relay when energized.

In connecting these relays in accordance with the preferred form of the invention, the signals 40, 41 and any other equipment which may be connected between the poles 151 is controlled by the cascade circuit A which includes the switch 146. The energization of the coil of the relay 142 controlling this switch is controlled by two circuits connected in parallel with each other, one indicated by the letter B, and the other indicated by the letter C. More particularly, one side of the relay 142 is connected to the power side of the battery 149 and the other side of the relay 142 is connected through the circuit B to the ground through the contact 147 of switch 200. The circuit C of the relay 142 runs through the switch 145, circuit C₁ and switch 144 or, alternatively therewith, through circuit C₂ which includes a normally open switch 154 of a relay 155 powered from a power pack 156 and provided with a condenser 157 of sufficient value that when the power goes on, the relay will have approximately a 1-second delay action before moving the switch 154 to its closed position and moving a second switch 158 to its open position.

Circuits C₁ and C₂ then converge as at 152, and circuit C continues through a foot actuated switch 160 located on top of the bowling alley rail 18 where a person stepping on the rail would open it. The other side of the switch 160 leads to the plate of the tube 120 thereby completing the second circuit C to ground under the control of the cascade photoelectric tubes 118.

The relay 51 is provided with a 3-second delay hold after deenergization and before energization thereof will operate to again close the switch 145. The coil thereof is under the control of the photoelectric cell 36 through a plate circuit D of the tube 141, and also, under the control of a circuit E having circuits E₁ and E₂ diverging at 161'. One of these circuits, E₁, includes the switch 158 and the switch 143. The other of these circuits E₂ runs through the switch 150 of the cutout relay 53b.

Relay 155 is connected to the contact 148 and is under the control of the switch 200 through the circuit F.

In the operation of the circuit shown in Fig. 5, when a ball is thrown over the foul line 12 the beam to the cell 34 is the first to be interrupted and the last to be released of the two foul line beams to the cells 34 and 36. When the top beam to photocell 34 is interrupted, switch 143 is closed and circuit E and E₁ sustains energization of the relay 51 to prevent the switch 145 from being opened, which would otherwise occur when the lower beam to photoelectric cell 36 alone is interrupted, in which case the relay 51 would be deenergized through circuit D. Circuit D, of course, is reenergized with the return of the lower light beam before the switch 143 is again opened. This permits a ball to pass over the foul line without indicating a false foul.

Thereafter, if a foul is committed at the foul

line by interrupting the lower beam 24 before the ball reaches the trip beam device 25 the bottom beam relay 51 is deenergized by the only circuit maintaining energization at that time, namely, circuit D, since switches 143 and 150 are open in alternative circuits E₁ and E₂, respectively. When the switch 145 is permitted to open, it remains open for three seconds, and when the ball interrupts the trip beam within that time, the switch 200 of the trip beam relay 53a breaks the circuit B which energizes the relay 142. With circuit C broken at 145, and circuit B broken at 200, deenergization of the cascade relay 142 follows immediately to close the switch 146 and operate the equipment including the means for calling of a foul.

If, however, one of the cascade beams is interrupted instead of the lower foul line beam before the ball reaches the trip beam device 25, current flow through the amplifier 120 is stopped with the same effect upon the circuit C as the opening of the switch 145. This is also true if the treadle switch 160 was stepped on or any other normally closed switch in series therewith is opened which is connected across the leads indicated at 161, such as wall switches, etc.

If a foul is committed by interrupting the bottom beam after the ball trips the trip beam and before tripping the cutout beam deenergization of the cascade relay 142 will take place immediately since once the trip beam is interrupted the relay 53a thereafter remains deenergized for ten seconds.

However, once the trip beam is interrupted, the relay 155 is energized through the circuit F and switch 200. There will be, however, a 1-second delay after establishing the circuit F before the switch 154 will close, during which time interruption of the top beam 23 will open the switch 144. During this second, if the switches 144 and 154 are both open, the cascade is deenergized through the circuit C and a foul signal will be called. An infraction of the rules of play that will cause this operation of the device is commonly known as the "heel and toe" foul, where the heel rests upon the alley in front of the foul line and the toe extends out over the foul line above the ballway. This occurs only for a brief period of time, namely, the 1-second period of time, after which any interference with the top beam 23 will not operate to call a foul. Once the ball 15 has interrupted the cutout beam, the switch 150 of the relay 53b is closed, and the circuit E and E₂ established thereby maintains energization of the relay 51 so that any interruption of the lower beam will not operate to open the switch 145 and call a foul. This prevents a bowler from making an intentional foul with his foot after the ball has reached the pit of the alley.

However, in event a player is falling over the foul line and does not come in contact with the ballway and interrupt the cascade beams before the ball reaches the cutout beam, the operation of the cutout in no way affects the ability of the cascade beams and the relay 142 thereof to call a foul. The circuit B sustaining energization of the cascade relay 142 is broken when the switch 200 breaks contact with contact 147 and the current cutoff characteristic of the tube 120 interrupts the only other means sustaining energization of the relay 142. A capacity type of detector such as that described in our Patent No. 2,425,254 can be substituted for the cascade

photoelectric beams on the ballway to control the relay 142.

In Figs. 3 and 4 the control system is modified to include the cascade control 118 described in conjunction with Figs. 1, 2 and 5 without the cascade being subject to the operation of the cutout beam as already described in connection with Fig. 5. In Fig. 3 the cascade relay 120 and switch 146 shunt the switches 50 and 28, whereas in Fig. 4 the cutout relay 53b and switch 28 shunt the amplifier tube 60 of the lower beam relay 51 so that in either case an intentional foot fault committed by interrupting the lower beam after the ball has interrupted beam 27 and reached the pit of the alley will not cause a foul to be signalled or placed into operation any equipment controlled by the foul detecting circuits described, such as signals 40, 41, automatic pin setter 162 (Fig. 1) or any other equipment.

Consequently it will be seen from the drawings and the description thereof how the objects of the invention are attained, and although in some respects we are not able to account fully for the improved results which are attained by the apparatus and arrangement of elements and circuits of the invention, it should be understood that any attempt to analyze the theories believed to be responsible for these results is to be construed not as defining a mode of operation but merely as a possible explanation of certain physical, electrical or capacity phenomena which have been observed.

Although certain embodiments and preferred arrangements of the elements of the present invention have been shown and described herein, it will be apparent to those skilled in the art that various uses and modifications and changes may be made without departing from the spirit and substance of the invention.

What is claimed is:

1. For use with a bowling alley having a foul line dividing it into a runway and a ballway and having equipment associated with the alley including means for disclosing a commission of a foul, an apparatus including a device actuated by a body such as a bowler's foot present above and proximate to the foul line and constituting the sole means for detecting infractions of the rules of play at the foul line, a second device spaced from the first and actuated by a body touching the alley upon the ballway, means controlled by the operation of one of said devices for operating said equipment, and means actuated by a ball in motion beyond the second device for removing said foot detecting device from operation while maintaining operativeness of said second device.

2. For use with a bowling alley having equipment associated with the alley including means for disclosing a commission of a foul and having a foul line across which a bowling ball is delivered by a bowler when put into play, an apparatus including a device for detecting the presence of a body such as a bowler's foot proximate to and above the foul line, a device for detecting the presence of any portion of a bowler's body which contacts the alley within a predetermined distance beyond the foul line, a timer device associated with the first two devices for maintaining said detection for a predetermined period of time, means controlled by the operation of one of the first two of said devices for operating said equipment in combination with said timer device, and means located upon the alley beyond

the foul line responsive to the passage of a ball therepast for removing from operation said foot detecting device at a time ahead of the termination of said predetermined period of time.

3. In a signalling device for bowling alleys or the like having a foul line, a signal control circuit including two switches connected in parallel and controlled by relays respectively, means for detecting infractions of rules of play at the foul line for actuating one of said relays to close the circuit, means for detecting infractions of rules of play beyond the foul line for actuating the other one of said relays to close the circuit, timer means for maintaining closed the circuit thus closed by one of the switches for a predetermined time, and means including a switch for opening the circuit having the first of said switches in it in response to a ball passing a predetermined point on the alley beyond the foul line.

4. For a bowling alley, the combination of normally inoperative means for detecting infractions of rules of play at the foul line, an element controlling said means to allow a ball to pass over the foul line onto the ballway without actuating said means, a second normally inoperative means for detecting infractions of rules of play immediately beyond the foul line, means responsive to the passage of the ball beyond the foul line rendering both of said inoperative means operative, and a second ball responsive means spaced from the first ball responsive means rendering said first normally inoperative means inoperative for a short period of time.

5. For use with a bowling alley having a foul line dividing it into a runway and a ballway and having equipment associated with the alley including means for disclosing a commission of a foul, an apparatus including a device actuated by a body such as a bowler's foot present above and proximate to the foul line including a switch, a second device spaced from the first and actuated by a body touching the alley upon the ballway, means controlled by the operation of said devices separately for operating said equipment, timer means for maintaining actuation of both of said devices for a predetermined period of time, and means actuated by a ball passing a predetermined point beyond the foul line and beyond the second device for actuating said switch to remove said foot detecting device from operation prior to the expiration of said predetermined period of time.

6. For use with a bowling alley having equipment associated with the alley including means for disclosing a commission of a foul and having a foul line across which a bowling ball is delivered by a bowler when put into play, an apparatus including a device for detecting the presence of a body such as a bowler's foot proximate to and above the foul line, a device for detecting the presence of any portion of a bowler's body which contacts the alley within a predetermined distance beyond the foul line, means for detecting the passage of a ball beyond said predetermined distance, means controlled by the operation of said means and one of said devices jointly for registering the commission of a foul, and means responsive to the presence of a ball beyond the second device for removing said first device from operation.

7. In a signalling device for bowling alleys or the like having a foul line, a signal circuit including a switch, a relay controlling said switch, a control circuit including said relay and a plu-

11

rality of switches, two of which are connected in the circuit in parallel, means for detecting infractions of the rules of play beyond the foul line including a relay for actuating one of said two switches to close said control circuit, means for detecting infractions of rules of play at the foul line for actuating the other of said two switches to close the control circuit, and means responsive to the passage of a ball past a predetermined point on the alley beyond the foul line for actuating another one of said plurality of switches which is connected in series with said other of the two switches to open the circuit it closes.

8. For use with a bowling alley having a foul line dividing it into a runway and a ballway and having equipment associated with the alley including means for disclosing a commission of a foul, an apparatus including a device actuated by a body such as a bowler's foot present above and proximate to the foul line, a timer for maintaining actuation of said device for a predetermined period of time, a second device spaced from the first and actuated by the presence of a body touching the alley upon the ballway side of the foul line, a third device spaced from the other two devices beyond the second device upon the ballway and actuated by a body such as a ball in motion beyond the second device, means controlled by the joint operation of the third device and one of the other two devices for operating said equipment, and means responsive to the passage of a ball past a predetermined point on the ballway beyond the third device for removing the first device and the timer from operation while maintaining operativeness of said second device.

9. For use with a bowling alley having equipment associated with the alley including means for disclosing a commission of a foul and having a foul line across which a bowling ball is delivered by a bowler when put into play, an apparatus including a device actuated by a body such as a bowler's foot proximate to and above the foul line and constituting the sole means for detecting infractions of the rules of play at the foul line, a second device actuated by any portion of a bowler's body which contacts the alley within a predetermined distance beyond the foul line, a third device actuated by a body such as a ball in motion on the alley beyond said sec-

15

ond device, means controlled by the joint operation of one of the first two of said devices in combination with the third device for operating said equipment, and means located upon the alley at a point beyond said third device and responsive to the presence of a moving ball upon the alley for removing from operation the first device while maintaining operativeness of said second device.

10 5 10. In a signalling device for bowling alleys or the like having a foul line, a signal control circuit including a switch, a relay controlling said switch, means for detecting infractions of rules of play at the foul line for operating said relay, timer means including a circuit for sustaining the operation of said relay for a predetermined period of time after said relay is actuated, means responsive to the passage of a ball past a predetermined point on the alley beyond the foul line for removing said relay and timer means from operation by said detecting means, and means detecting infractions of rules of play beyond the foul line for operating said relay independently of said first detecting means and said responsive means.

11 15 20 30 35 40 45 50. For use with a bowling alley having a foul line dividing it into a runway and a ballway and having equipment associated with the alley including means for disclosing a commission of a foul, an apparatus including a device actuated by a body such as a bowler's foot present above and proximate to the foul line as a sole means for detecting infractions of the rules of play at the foul line, a second device actuated by a bowler's body touching the alley upon the ballway, means controlled by the operation of said devices separately for operating said equipment, and means actuated by a ball passing a predetermined point beyond the foul line for removing said first device from operation while maintaining operativeness of said second device.
